The ornamental design for a eleven petal flower shaped golf club divider for a golf bag as shown and described.

DESCRIPTION

FIG. 1 is a top perspective view of a 11 petal flower shaped golf club divider for a golf bag showing my new design in use;

FIG. 2 is a top plan view thereof;

FIG. 3 is a side elevational view thereof;

FIG. 4 is a front elevational view thereof; and,

FIG. 5 is a rear elevational view thereof.

The broken lines showing of a portion of a golf bag in FIGS. 1, 3, 4 and 5 are for illustration purposes only and forms no part of the claimed design.

FIGS. 2-5 are drawn in larger scale.
